UNITED STATES PATENT OFFICE

153,898

DESIGN FOR A CURTAIN OR DRAPERY
FESTOON RING

Manfred J. Pollak, Chicago, Ill., assignor to Western Newell Mfg. Co., Freeport, Ill., a corporation of Illinois

Application October 15, 1947, Serial No. 141,914

Term of patent 14 years

(Cl. D21—1)

To all whom it may concern:

Be it known that I, Manfred J. Pollak, a citizen of the United States residing at Chicago, in the county of Cook and State of Illinois, have invented a new, original, and ornamental Design for a Curtain or Drapery Festoon Ring, of which the following is a specification, reference being had to the accompanying drawing, forming part thereof.

In the drawings:

Figure 1 is a front plan view of a curtain or drapery festoon ring showing my new design.

Figure 2 is a rear plan view.

Figure 3 is an edge elevational view, and

Figure 4 is an edge elevational view thereof, taken at substantially right angles to the position shown in Figure 3.

I claim:

The ornamental design of a curtain or drapery festoon ring, as shown.

MANFRED J. POLLAK.
